TYPOGRAPHICAL COMPOSING MACHINE

Louis Rossetto, Kings Point, N. Y., assignor to
Mergenthaler Linotype Company, a corpora-
tion of New York

Application July 9, 1952, Serial No. 297,885

3 Claims. (Cl. 199—32)

1

This invention relates to typographical composing machines, such as Linotype machines of the general organization represented in U. S. Letters Patent to O. Mergenthaler, No. 436,532, wherein circulating matrices and spacebands are selectively composed in an assembler elevator, the elevator raised to line transfer position, the composed line transferred therefrom and presented to the face of a mold between a pair of vise jaws for the casting of a typebar or slug, and the matrices and spacebands thereafter separated and returned to their respective storage magazines for further use.

In these machines, the matrices and spacebands are assembled in the elevator by a rotary starwheel and against a yielding line resistant finger which serves to support the line endwise. The finger is mounted at the end of an assembler slide, which slide, although always under spring tension is acted upon by a friction brake which permits it to move under the influence of incoming matrices and spacebands but prevents its return movement under the influence of the spring. When the composition of the line has been completed and the elevator raised the assembler slide brake is released and the slide and finger are returned by the spring to line receiving position preparatory to the composition of the next line.

When the line has been presented to the mold between the vise jaws the line is justified that is to say the wedge-shaped spacebands are driven upwardly to expand the line between the jaws. Thereupon the molten metal is introduced into the mold and against the composed line and unless the line is fully expanded between the jaws a safety device prevents the casting operation from taking place to prevent the molten metal from being forced or "squirted" through any openings or spaces in the line. Thus when the line is not long enough to be fully justified the line is distributed without having been instrumental in producing a typebar and the line is lost. On the other hand, the length of the line must not exceed the pre-adjusted distance between the vise jaws, otherwise the line cannot be received in the casting position between the jaws and jamming will occur. When such jamming occurs, the machine is adapted to be automatically disabled, but nevertheless some damage may result to the jaws or to the matrices and, in addition, it then becomes necessary to reverse the main cam shaft of the machine by hand in order to recondition the machine for further operation. It is evident then that the composition of lines which are either too long or too short is highly undesirable.

2

The composition of lines to the proper measure has always depended largely upon the discretion of the operator, although various safety devices have been heretofore proposed to prevent the transfer to the casting mechanism of lines which are too long or too short of a desired measure. However, now that it is becoming common to equip line-casting machines with tape control units, automatic safety devices to take the place of the operator's judgment are essential.

The present invention is directed to an automatic safety device for this purpose. Accordingly, the assembler slide is provided with a device which may be adjusted thereon according to the length of line which it is desired to compose. When the composition of the line is completed, the friction brake is first momentarily released to tighten the line to its true measure, and the position of the pre-adjusted device will then permit or prevent the operation of a locking mechanism for the assembler elevator according to the length of the line.

These and other features of the present invention will be more fully described in the detailed specification which follows.

Referring to the drawings:

Fig. 1 is a front elevation of the assembling mechanism of a Linotype machine illustrating the present safety mechanism and the electrical control circuits therefor; and

Fig. 2 is a side elevation of the keyboard and the elevator locking mechanism.

The matrices and spacebands are individually and selectively released from a magazine (not shown) by the automatic operation of a keyboard 35 A and fall by gravity onto the upper stretch of an inclined continuously moving belt 1, passing around a lower drive pulley 2 and an upper idler pulley (not shown), whereupon they are directed through a guide chute formed by lower rails 3 and an upper chute finger 4 to and in front of a rotating starwheel 5 which stacks them, one by one, in line in an assembler elevator B against a yielding line resistant finger 6. After the line has been composed, the assembler B is manually or automatically elevated and the composed line transferred to casting position.

The line resistant finger is carried at the end of a long assembler slide 7. The slide is mounted to move freely to the left under the influence of the incoming matrices which press against the line resistant finger, although its yielding movement is always under the restraint of a clock spring 8. The retrograde movement of the slide to the right under the tension of the spring is resisted by a pivotal brake 9 having parallel fric-

tion surfaces which grip the upper and lower edges of the slide. When the brake 9 is in a vertical position, the parallel surfaces do not interfere with the slide and, hence, the spring is free to return the slide to the right or, at least, as far as the assembled matrices and spacebands allow it to be moved. Normally, however, the brake is acted upon at its lower end by a spring 10, attached to a stationary guide 11, which serves to pivot the brake from the vertical to the inclined locking position. As the matrices and spacebands are assembled by the starwheel against the finger 6, the assembler slide moves along, the friction surfaces of the brake yielding slightly and allowing the slide to move to the left.

When composition of the line has been completed, the assembler elevator B may be raised by a hand lever (not shown) connected to a long horizontal rock shaft 12 (see Fig. 2), which latter is in turn connected to the elevator through horizontal and vertical links 13 and 14, respectively. When the machine is operated automatically, the hand lever is operated by power taken from the intermediate drive shaft of the machine and transmitted through a clutch arrangement to periodically operate a shaft 15 (see Fig. 1). The shaft 15 is equipped with a cam (not shown) which raises the elevator. The specific details of the elevator lifting mechanism per se form no part of this invention and are shown and described with certain minor variations in U. S. Patent Nos. 2,006,848, 2,091,286, and 2,163,390. It suffices to say, for present purposes, that the hand lever is adapted to yield when the movement of the elevator is unduly resisted. As the line is raised by the elevator, the brake 9 is released in the usual manner to permit the return of the slide 7 and the finger 6 to their extreme rightward or line receiving position.

Coming now to the present invention, the elevator raising link 13 is provided with a bracket 16 having a sidewardly projecting lip 16a, which lip is normally engaged by a pivotal latch 17 mounted on the side of the keyboard A. The latch is maintained in locking position by a small tension spring 18 (Fig. 2). When the link is thus locked, it is impossible to raise the elevator B either by hand or by power.

The latch 17 is adapted at all times to be maintained in locking position except when the composed line is within certain limits of the predetermined desired measure. When the line is within these limits, an electrical rotary type solenoid 19 is energized, thereby rotating the vertically disposed portion of the armature 19a in the direction indicated by the arrow in Fig. 2. The vertically disposed portion of the armature, in turn, engages a projecting lip 17a of the latch 17 and pivots the latch to unlocking position, as illustrated by the broken lines in Fig. 2.

Preparatory to the rise of the elevator B, the brake 9 is momentarily released in order to remove any slack in the line. Obviously, unless all the slack is removed, it is impossible to obtain a true measure of the line. The mechanism for accomplishing this initial release of the brake from an automatic tape control unit is described and claimed in a pending application of L. Rossetto, Ser. No. 247,501, filed September 20, 1951. However, the stated purpose in that case is to tighten the line to straighten up the end or last matrix and to insure that it is properly positioned within the assembler during its elevation, rather than to remove the slack to obtain a true meas-

urement thereof, as in the present case. The releasing of the brake may be accomplished manually by a horizontal lever 20 pivoted at 20a on the front of the machine. The lever 20 is provided with a downwardly depending arm 20b, which carries an adjustable screw 20c. The screw 20c is in contact with the brake 9, and when the lever 20 is depressed, that is, rotated in a clockwise direction, the screw moves the brake to release position. The balance of the lever 20 is such that its normal position is an inoperative position, where it has no effect on the brake or where the effect is such that it is overcome by the tension of the spring 10.

15 The automatic operation of the lever 20 to release the brake for the purpose stated is accomplished by a rotary type solenoid 21, having a rotatable arm 21a engaging a vertically disposed pin 20d of the lever. Power to energize the solenoid 21 may be taken from a normal 110 volt A. C. supply, as indicated, and to avoid placing full line voltage on the machine in the interest of safety, a transformer T is utilized to reduce the voltage to 24. The 24 volt A. C. is transformed 25 into direct current by a selenium rectifier, designated in Fig. 1 by the reference character R.

The timed operation of the solenoid 21 is controlled from the elevator raising shaft 15 of the automatic tape control unit. Thus, the rearmost extremity of the shaft 15 carries a cam 22 which, through a vertically movable pin 23, controls the opening and closing of contacts 24a and 24b of a leaf type switch generally designated 24. Both the pin 23 and the switch 24 are supported by an inverted L-shaped bracket 25.

The opening and closing of the switch 24 controls the operation of the solenoid 21. The relationship between the elevator raising shaft 15 and the cam 22 is such that normally the contacts of the switch are held apart or open by the pin 23. In response to a signal on the control tape, power is transmitted to the shaft 15, rotating it through one complete revolution to effect the elevation of the assembler B. At the initial stage of the cycle, however, and before any actual movement is imparted to the elevator B, a depression 22a of the cam 22 permits the pin 23 to descend and close the switch 24 to effect momentary operation of the brake releasing solenoid 21. Later, the high portion 22b again opens the switch 24, permitting the solenoid to restore itself to inoperative position, the entire operation taking place before the elevator begins its ascent.

55 When the composition of the line is complete and the slack thus removed, the extent of the leftward displacement of the slide 7 from its extreme rightward position affords an accurate measurement of the length of the line composed. Accordingly, the slide 7 is provided with a rider or clamp 30, which may be adjusted along the slide with reference to a scale 7a thereof and with respect to a leaf-type switch, generally designated 31, mounted on the front face plate 60 cover just above the assembler slide. The switch 31 comprises upper and lower leaf contacts 31a and 31b, insulated from each other, and the lower contact 31b is provided with a small roller 31c. The switch 31 is normally open, and it is closed 65 only when the roller 31c makes contact with the top surface of clamp 30. The closing of the switch 31 establishes a circuit from the rectifier R to the solenoid 19, which, as we have seen, releases the latch 17 and makes possible the raising 70 of the assembler elevator B.

Thus, as the clamp 30 moves leftwardly during the composition of the line, for a given setting of the clamp the switch 31 is closed only for a line of a certain length. When the line is composed short of the desired measure, the clamp will be in a position to the right of the roller 31c, and when the line is composed beyond the desired measure, the clamp will have traveled beneath and to the left of the roller, as indicated by the broken line showing in Fig. 1.

To facilitate the travel of the clamp past the roller 31c in either direction, the upper corners of the clamp are beveled. Actually, the upper cam surface of the clamp is about 3 ems wide so that the switch will remain closed for a 3 em horizontal movement of the assembler slide. Naturally, a clamp of less width could be employed, if desired.

By way of summary, the latch 17 is normally spring urged into locking engagement with the projection 16a of the elevator raising link 13 and in this position prevents the raising of the elevator. Before composition, the clamp 30 is adjusted with respect to the scale 7a according to the length line which is to be assembled and for which the vise jaws are pre-set to receive. As incoming matrices and spacebands are assembled in the elevator against the finger 6, the slide 7 gradually yields to the left, carrying the clamp 30 therewith. When the composition of the line is complete, the lever 20 is depressed to remove any slack in the line, and if the machine is equipped with an automatic tape control unit, the lever 20 is automatically momentarily tripped by the solenoid 21. If the line has been composed within the proper 3 em limits, the clamp 30 will be positioned under the roller 31c of the switch 31, thereby completing a circuit to the latch releasing solenoid 18 to permit the raising of the elevator. If the line has been composed either short or beyond the allowable limits, the switch 31 will be open, and the latch will remain in its normal elevator locking position. When the machine is under automatic operation,

a slip clutch through which power is transmitted from the shaft 15 to the elevator lifting handle, prevents any damage to the machine.

The invention has been shown and described in 5 preferred form, but obviously many variations and modifications may be made therein and in its mode of application which will still be comprised within its spirit. It is understood, therefore, that the invention is not limited to any specific form 10 or embodiment, except insofar as such limitations are specified in the appended claims.

Having described the invention, the following 15 claims are made:

1. In a typographical composing machine, the 20 combination of an assembler elevator wherein the line is composed, a lock normally operative to prevent the rise of the elevator, an electrical solenoid to control the release of said lock, a normally open electrical switch to control the operation 25 of said solenoid, an assembler slide yieldable during the composition of the line, and a rider settable on said slide in a predetermined position in relation to said switch for a given line length, said rider being adapted to close the switch when the length of the line is within the allowable range of the pre-set measure.

2. A combination according to claim 1 including 30 an assembler side brake to normally prevent retrograde movement of the slide, and time controlled means for releasing said brake prior to any movement of the assembler elevator to tighten up the line.

3. A combination according to claim 1 wherein 35 the width of the rider determines the range over which the elevator lock will remain inactive.
